UNITED STATES PATENT OFFICE

ROYCE M. STRICKLAND, OF NEW HAVEN, CONNECTICUT, ASSIGNOR TO THE GEOMETRIC TOOL COMPANY, OF NEW HAVEN, CONNECTICUT, A CORPORATION

SELF OPENING DIE-HEAD

Application filed May 28, 1931. Serial No. 540,542.

This invention relates to improvement in self-opening die-heads and particularly to that type of die-heads commonly referred to as "pull-off" die-heads and provided with a chaser-carrier slidably mounted with respect to certain features of the die-head, so that a forward draft exerted by the work will effect the tripping and hence the automatic opening of the die-head.

The main object of this invention is to provide a durable and rugged self-opening die-head of the character referred to, constructed with particular reference to compactness, smoothness and accuracy of performance, and its capacity for uninterrupted severe use over long periods without suffering derangement or other failure.

With the above and other objects in view as will appear from the following, my invention consists in a self-opening die-head having certain details of construction and combination of parts as will be hereinafter described and particularly recited in the claims.

In the accompanying drawings:

Fig. 1 is a view in side elevation of a self-opening die-head constructed in accordance with my invention;

Fig. 2 is a view thereof in front elevation;

Fig. 3 is a central longitudinal sectional view thereof, taken on the line 3—3 of Fig. 2, but on a larger scale, the parts being shown in the positions due to them when the chasers are in their cutting position;

Fig. 4 is a corresponding view, but showing the parts in the positions due to them when the latching-mechanism is about to release the chaser-operating member to permit the retraction of the chasers;

Fig. 5 is a corresponding view, but showing the parts in the positions due to them when the die-head has been fully tripped for the retraction of the chasers;

Fig. 6 is a view in transverse section taken on the line 6—6 of Fig. 3;

Fig. 7 is a broken detail sectional view taken on the line 7—7 of Fig. 6;

Fig. 8 is a similar view taken on the line 8—8 of Fig. 6;

Fig. 9 is a corresponding view on the line 9—9 of Fig. 2;

Fig. 10 is a view in front elevation of the mounting-member detached;

Fig. 11 is a side view thereof with the shank broken away;

Fig. 12 is a top or plan view thereof with the shank broken away;

Fig. 13 is a broken longitudinal sectional view taken on the line 13—13 of Fig. 10;

Fig. 14 is a side view of the chaser-carrying member, detached;

Fig. 15 is a view thereof in rear elevation;

Fig. 16 is a view in front elevation of the latching-member detached; and

Fig. 17 is an edge view thereof.

The particular self-opening die-head herein chosen for the illustration of my invention includes, as shown, a mounting-member generally designated by the numeral 20 and consisting of a rearwardly-projecting shank 21 by means of which the tool may be mounted in the turret 22, indicated by broken lines, of any suitable threading-machine. The forward portion of the mounting-member 20 constitutes a head 23 consisting of an annular flange 24 formed integral with the shank 21 and a separately-formed ring 25 corresponding in diameter to the diameter of the flange 24 to which it is secured by a pair of screws 26—26.

The ring 25 just referred to is made separate from the flange 24 and shank 21 solely for the purpose of convenience in manufacture, but for all functional purposes constitutes an integral element and may be so viewed in the present invention.

The ring 25 of the mounting-member 20 is diametrically cut or bifurcated to provide a forwardly-facing diametrical coupling-groove 27 (Figs. 10 and 12) into and beyond which forwardly extends a guide-sleeve 28 formed integral with the flange 24 and shank 21, and through which extends, as well as through the said shank, an axial bore or passage 29 to provide clearance for the work as the same is being threaded.

Slidably mounted upon the guide-sleeve 28 is a reciprocating chaser-carrying member 30 provided with an axial bore 31 extending

completely therethrough and receiving the said guide-sleeve 28. The said chaser-carrying member 30 is formed with a rearwardly-extending coupling-tang 32 having two flat faces and two convex faces, and fitting into the coupling-groove 27 in the ring 25 of the mounting-member 20, which it closely fits, with freedom only for axial sliding movement.

10 The chaser-carrying member 30 is provided in its forward face with four (more or less) radial guide-grooves 33, each receiving a radially-movable chaser 34, which chasers are retained in place against forward displacement by segmental plates 35 secured to the forward face of the said chaser-carrying member 30.

15 The outer ends of each of the chasers 34 are rearwardly and inwardly-inclined to form cam-surfaces 36, as shown in Fig. 9, for engagement with similarly-sloping cam-surfaces 37 formed upon the forward inner corner of a chaser-operating sleeve 38 mounted upon the die-head structure with capacity for axial sliding movement and bearing at its forward end upon the periphery of the chaser-carrying member 30, and internally-threaded at its rear end for the reception of the forward end of an adjusting-ring 39, which slides partly upon the periphery of the ring 25 of the mounting-member 20, as well as the flange 23 thereof, and also upon the periphery of the rearwardly-extending tang 32 of the chaser-carrying member 30.

20 30 The chaser-operating member 38 and adjusting-ring 39 above referred to, normally function as a unit but are made adjustable with respect to each other for the purpose of permitting an adjustment of the cutting diameter of the chasers, as will hereinafter appear.

25 40 The adjusting-ring 39 which, as above pointed out, is unitary with the chaser-operating sleeve 38, is formed in its interior with an annular groove 40, the forward wall of which forms a locking-shoulder 41 for engagement with the forward upper corner of a radially-movable plate-like locking-member 42 mounted in a transverse tangential groove 43 formed in the upper convex face of the coupling-tang 32 of the chaser-carrying member 30.

45 55 The locking-member 42 referred to is normally urged radially outward by means of a pair of springs 44-44 housed within complementary pockets, respectively formed in the inner face of the said locking-member and in the bottom-wall of the groove 43, as clearly shown in Fig. 6, and is limited in its outward movement by a retractable stop-plunger 45 having its stem 46 riding in a passage 47 in the chaser-carrying member 30 and projecting rearwardly into the groove 43 and into a notch 48 in the upper arcuate face of the said locking-member. The stop-plunger 45 is pro-

vided with a head-portion 49 bearing in a bore 50 coaxial with the bore 47 and housing a spring 51 exerting a constant effort to move the said plunger 45 rearward so as to project the rear end of its stem 46 into the notch 48 in the locking-member 42.

50 55 For the purpose of retracting the locking-member 42 from engagement with the locking-shoulder 41 of the sleeve 38, I provide the said locking-member at its respective opposite ends with operating-ribs 52-52 having their upper surfaces forwardly and inwardly inclined as shown, and respectively entered into grooves 53-53 formed in the respective opposite walls of the groove 27 in the ring 25 before referred to. The respective upper walls of the said grooves 53-53 are forwardly and inwardly inclined in conformity with the slope of the ribs 52-52 of the locking-member 42 to provide cam-surfaces 53^a-53^a engaging the said ribs for the purpose as will hereinafter appear.

60 65 The chaser-operating sleeve 38 together with the adjusting-ring 39, is urged rearwardly with respect to the chaser-carrying member 30 by means of a pair of complementary spring-pressed plungers 54-54 (Figs. 6 and 7) reciprocating within bores 55-55 in the forward portion of the chaser-carrying member 30 and bearing at their rear ends against the forward end of the adjusting-ring 39. The said plungers 54-54 are chambered as shown in Fig. 7, and each partially houses a spring 56 bearing at its rear end in the said plunger and at its forward end against one of the faces of the retaining-plate 35, so as to exert a constant effort to move the adjusting-ring 39 and hence the chaser-operating sleeve 38 rearward with respect to the chaser-carrying member 30. To permit the free play of the plungers 54, the adjacent periphery of the ring 25 of the mounting-member is formed with semi-circular clearance-grooves 57-57.

70 75 Similarly, the chaser-carrying member 30 is constantly urged rearwardly with respect to the mounting-member 20 by means of a pair of complementary springs 58-58 respectively encircling screws 59-59 (Figs. 6 and 8) screwed into and rearwardly projecting from the chaser-carrying member 30. Each of the said screws 59 and its complementary spring 58 extends within a bore 60 formed in the ring 25 on each of the respective opposite sides of its groove 27. Each of the said springs 58 bears at its rear end against the under-side of the head of its complementary screw 59 and at its forward end bears against a sliding bushing 61. The head of each of the said bushings normally bears against an annular stop-shoulder 62 forming a feature of each of the bores 60, while the forward ends of the said bushings bear against the rear face of the enlarged forward end of the chaser-carrying member 30.

As before stated, the chaser-carrying member 30 is mounted for axial reciprocation upon the guide-sleeve 38 of the mounting-member 20 with respect to which it may move either forwardly or backwardly from the position in which it is shown in Fig. 3.

To provide a yielding contact when the tool as a whole is advanced to engage the chasers 34 with the work, I employ a pair of complementary plungers 63—63 mounted partially in the rear end of the ring 25 and partially in the flange 24 of the mounting-member 20, as shown in Figs. 3, 4 and 5. The forward ends of the said plungers engage the rear face of the chaser-carrying member 30 and each is urged forwardly by a spring 64 and limited in such forward movement by being provided with an annular flange 65 engaging a stop-shoulder 66 in the said ring 25.

The adjusting-ring 39 owing to its threaded connection before described with the chaser-operating member 38, is rotatable with respect to the latter for the purpose of adjusting the position of the locking-shoulder 41 and hence regulating the cutting diameter of the chasers 34 and is locked in any given position of adjustment by a latch 67 reciprocating in a bore 68 formed in the said chaser-operating sleeve and urged rearwardly by means of a spring 69 to engage its rear end with any given one of an annular series of forwardly-facing pockets 70 formed in the said adjusting-ring 39.

For the purpose of moving the chaser-operating sleeve 38 forwardly to move the chasers into their cutting positions, after the die-head has been tripped, I employ a resetting-finger 71 having a rounded terminal 72 projecting within a radial socket 73 formed in the chaser-carrying member 30, and located in a recess 74 formed in a lug 75 offsetting from and formed integral with the said operating-sleeve 38, as shown in Fig. 6.

The resetting-finger 71 referred to is mounted upon a squared portion 76 of a resetting-shaft 77 rocking in a bore 78 in the lug 75 and formed at its outer end with an integral resetting-arm 79 adapted to be engaged with any of the customary features of a threading machine for resetting the die-head as will hereinafter appear.

My improved die-head operates in a general way in accordance with that class of self-opening die-heads known as the "pull-off" type.

With the parts in the positions in which they are shown in Figs. 1 to 3 inclusive, the chasers 34 may be engaged with the work or the work with the chasers. When the desired length of thread has been cut, the feed of the work with respect to the die-head or the feed of the die-head with respect to the work, as the case may be, is stopped, after which the continued rotation of the work will act

through the chasers 34 to draw the entire chaser-carrying member 30 forwardly with respect to the mounting-member 20. The relative forward movement of the chaser-carrying member 30 as just described, will bodily carry with it the locking-member 42 together with the chaser-operating sleeve 38 and adjusting-ring 39.

As the locking-member 42 is bodily moved forward, as above described, its offsetting-ribs 52 will be caused to ride down the slope of the upper walls 53^a—53^a of the complementary grooves 53 formed in the opposite walls of the coupling-groove 27 with the effect of gradually moving the said locking member inward to disengage the same from the annular locking-shoulder 41 in the adjusting-ring 39.

The parts will now have assumed the positions in which they are shown in Fig. 4, at which time the locking-member 42 is shown at the instant it is being cleared from the locking-shoulder 41.

The instant that the locking-member 42 is fully cleared from the annular locking-shoulder 41 of the adjusting-ring 39, the springs 56—56 will act to snap the chaser-operating sleeve 38, together with the said adjusting-ring 39, rearward to permit each of the chasers 34 to move radially outward out of engagement with the work under the urge of chaser-retracting springs 80 (Fig. 9), one of which is provided for each of the said chasers.

The instant that the chasers 34 move radially outward out of engagement with the work, as above described, the springs 58—58 will assert themselves and move the chaser-carrying member 30 from the position into which it has been pulled by the draft exerted by the work (Fig. 4) rearward to its normal position of equilibrium with respect to the mounting-member 20. The parts will now have assumed the positions in which they are shown in Fig. 5.

When it is desired to perform another threading operation a relatively-rearward force exerted upon the resetting-arm 79 will rock the shaft 77 and hence the resetting-finger 71, with the effect of sliding the chaser-operating sleeve forwardly together with the adjusting-ring 39, which latter will ride over the locking-member 42, momentarily depressing the same until the annular locking-shoulder 41 in the said ring has ridden past the forward edge of the said locking-member, at which time the latter will snap outwardly into the groove 40 in position to engage the said shoulder 41 and prevent the rearward movement of the said ring and the sleeve 38 until such time as the die-head is again tripped.

The forward sliding movement of the chaser-operating member 38 and the adjusting-ring 39 will also cause the cam-surfaces 37 at the forward edge of the said ring to ride

over the cam-surfaces 36 upon the respective chasers 34 and concurrently move each of the latter inwardly into position for cutting a thread. The parts have now been restored 5 to the positions in which they are shown in Figs. 1 to 3 inclusive.

The resetting of the die-head as above described as effected by a rearward force applied to the resetting-arm 79 may be accomplished in any approved manner, such as during the indexing of the turret in which the die-head may be mounted, during which indexing an abutment engages the said resetting-arm for swinging the same rearwardly, 10 as described; or, if desired, the resetting-arm 15 79 may be manually operated.

It will be appreciated that as a threading operation is going on, there will be a strong tendency to rotate the chaser-carrying member 30 with respect to the mounting-member 20, which tendency is effectively resisted without occasioning cramping by the coupling-tang 32 engaging with the walls of the coupling-groove 27 in the ring 25 forming a 25 feature of the mounting-member. Furthermore, by locating the locking-member 42 in the tang 32 in position to be retracted by inclined surfaces in the respective opposite walls of the said coupling-groove 27, I not 30 only provide a convenient and compact arrangement of parts but assure the uniform retraction of the said locking-member and avoid any appreciable cramping action thereupon, so that the die-head remains sensitive 35 to relative forward drafts exerted by the work upon the chaser-carrying member to effect the tripping of the die-head.

It will be understood by those skilled in the art that my invention may assume varied 40 physical forms without departing from my inventive concept and I, therefore, do not limit myself to the specific embodiment herein chosen for illustration, but only as indicated in the appended claims.

45 I claim:

1. In a pull-off die-head, the combination with a mounting-member formed with a forwardly-facing diametrical coupling-groove provided in each of its respective opposite side walls with a forwardly-and-inwardly-inclined shoulder; of a chaser-carrying member carried by the said mounting-member with capacity for relative axial sliding movement with respect thereto and provided with 50 a rearwardly-extending coupling-tang having sliding engagement with the walls of the forwardly-facing diametrical coupling-groove in the said mounting-member; chasers mounted in the said chaser-carrying member; a chaser-operating member operatively engaged with the said chasers for controlling the same and formed with a locking-shoulder; and a locking-member mounted in the coupling-tang of the said chaser-carrying member in position to engage the lock- 55 ing-shoulder of the said chaser-operating member and having each of its opposite ends engaged respectively with the inclined shoulders in the coupling-groove of the said mounting-member. 70

2. A pull-off die-head as set forth in claim 1 and having the said locking-member bearing at its respective opposite ends against the side-walls of the coupling-groove in the said mounting-member and provided at each 75 of its opposite ends with an offsetting-rib engaging the inclined shoulders in the said coupling-groove. 75

3. A pull-off die-head as set forth in claim 1 and having the coupling-tang of the chaser-carrying member formed with two flat faces and two concentric convex faces and having a transverse notch formed in one of the said convex faces and opening through the complementary flat side faces to provide a guide- 80 way for the said locking-member. 80

4. In a pull-off die-head, the combination with a mounting-member formed with a forwardly-facing diametrical coupling-groove provided in each of its respective opposite side walls with a forwardly-and-rearwardly-inclined shoulder, and also having a guide-sleeve forwardly-projecting into the said coupling-groove; of a chaser-carrying member having an axial bore for the sliding reception of the guide-sleeve of the said mounting-member and provided with a rearwardly-extending coupling-tang also sliding upon the said guide-sleeve and having sliding engagement with the walls of the forwardly-facing diametrical coupling-groove in the said mounting-member; chasers mounted in the said chaser-carrying member; a chaser-operating member operatively engaged with the said chasers for controlling the same and formed with a locking-shoulder; and a locking member mounted in the coupling-tang of the said chaser-carrying member in position to engage the locking-shoulder of the 95 said chaser-operating member and having each of its opposite ends engaged respectively with the inclined shoulders in the coupling-groove of the said mounting-member. 100

5. In a pull-off die-head, the combination with the complementary mounting-member and chaser-carrying member thereof, one of the said members being formed with a diametrical coupling-groove provided in each of its respective opposite side walls with an 110 inclined shoulder, and the other of the said members being formed with a tang sliding into the said diametrical groove of the other member; of chasers mounted in the said chaser-carrying member; a chaser-operating member operatively engaged with the said chasers for controlling the same and formed with a locking-shoulder; and a locking-member mounted in the coupling-tang of the 115 aforesaid complementary member so provid- 120

ed in position to engage the locking-shoulder of the said chaser-operating member, and having each of its opposite ends engaged respectively with the inclined shoulders in the coupling-groove in the other of the said complementary members.

In testimony whereof, I have signed this specification.

ROYCE M. STRICKLAND.
